TIE BARS FOR SPACING CURB FORMS

Frank Torrelli, 40 Arthur St., Cheektowaga, N.Y.

Filed July 5, 1955, Ser. No. 519,699

2 Claims. (Cl. 25—118)

This invention relates to tie bars for spacing the forms or molds used in the construction of poured concrete curbs.

The particular object of the invention is to provide tie bars for spacing the forms for poured concrete curbs which are easily applied, securely hold the forms together and are easily removed from the forms when the concrete curb as set.

Other objects and advantages will be apparent from the following description and drawings in which:

Fig. 1 is a transverse, sectional view through an assembled curb form including the tie bars of the present invention.

Fig. 2 is a fragmentary top plan view of the form assembled as shown in Fig. 1.

Fig. 3 is a fragmentary, front elevational view of the curb form assembled as shown in Figs. 1 and 2.

Fig. 4 is a perspective view of the tie used to fasten the stakes at a fixed distance with reference to each other.

Fig. 5 is a perspective view of the wedge pin used in conjunction with the tie shown in Fig. 6.

The concrete form illustrated is designed for use in the construction of curbs for streets, roads and the like. The form sections compose a mold adapted to be staked to the ground and having an open bottom and top. The two sides of the curb are molded by form sections which are designed to be joined end to end to produce a curb of the desired length. Each section of the form comprises as principal elements three rails, which are preferably sheet steel channel members. In each form section, the rear face of the curb, i.e., the side remote from the road or street, is molded against a single upright horizontal rail 20. On the front, each section of the form comprises a lower horizontal rail 21 that is also preferably upright and an upper horizontal rail 22 which rests on the rail 21 and is preferably inclined rearwardly.

The rear or back rail 20 comprises a web 23 having longitudinal top and bottom flanges 24 and 25, respectively. The outer edge of each of the flanges is preferably turned vertically and inwardly as shown at 26 and 27 to provide additional strength and rigidity for the channel member 20 and an end block 31 is secured, by suitable means such as welding, within the channels formed between the inturned edges 26 and 27 of the flanges 24 and 25 and the web 23 at one end of each of the rails 20. Each of the blocks 31 has a portion projecting longitudinally from the corresponding end of the rail 20, the outer end of the projecting portion being beveled so as to be pointed, as indicated at 32, thereby to facilitate the insertion of this block into the end of another mating rail member 20.

Each of the lower front channel members or rails 21 can be of similar construction to the back rail 20, having a web 42 and longitudinal top and bottom outwardly projecting lateral flanges 43 and 44. The edges 46 and 47, respectively, of the flanges 43 and 44 are turned inwardly and preferably aline with each other parallel to the web 42. Each of the rails is also provided at one

2

end with an end block 48 similar to the block 31, the outwardly extending portion of each block 48 being also pointed, as indicated at 49, to facilitate insertion of this block into the next succeeding mating rail 21.

5 A bracket or clip, indicated at 52, is shown for receiving the stakes 54, these stakes being driven into the ground and cooperating with similar stakes 54 at the back of the form both to hold the form reliably positioned on the ground and also to hold the sections of the forms 10 in assembled and properly spaced relation to one another. Each stake bracket or clip 52 is secured to the end of the rail 21 opposite its block 48 and within the channel provided by the web 42 and the flanges 43 and 44. It consists of an L-shaped bracket having a leg 55 15 which projects outwardly from the web 42 and a leg or flat finger 56 extending from the outer edge of the leg 52 in a direction generally parallel with the web 42. The bracket is provided with an attaching flange 57 which can be secured, as by welding, to the front or 20 channel face of the web 42. The leg or flat finger 56 of the stake attaching bracket or clip 52 is set outwardly from the vertical plane of the flanges 46 and 47 such distance that each stake 54 can be driven downwardly and have one of its sides engaging the flanges 46, 47 and 25 its opposite side engaging the leg or flat finger 56 of the bracket or clip 52. This fit is preferably quite snug, in fact, it is desirable that the bracket 52 be sprung outwardly slightly to accommodate the stake and for this purpose, the outer vertical extremity of the leg or flat 30 finger 56 is preferably provided with an outwardly curving lip 58.

The front surface of the concrete curb, according to the present invention, is also preferably formed with a rearwardly inclined top portion. The mold for this 35 portion of the front surface is provided by the upper front channel members or rails 22, each of which is of generally similar form to the rails 20 and 21 and has a web 60, longitudinal top and bottom outwardly projecting flanges 61 and 62, the edges 63 and 64, respectively, of which are preferably turned inwardly in opposed facing relation. Each rail 22 also preferably has a block 65 welded in one of its ends and each block 65 has a pointed end 66 projecting outwardly from its rail 22 and to be inserted into the end of a succeeding mating 45 rail 22. The bottoms of the channel members or rails 22 rest on the tops of the lower front rails 21 and the rails 22 are supported in the desired inclined position by a division and spacing plates 68 which are placed transversely between the front and rear channels or 50 rails at regular intervals.

Each of the division plates 68 is preferably formed of sheet metal of substantial thickness so as to be stiff and resist bending and the main portion of each plate is shaped as a rectangle with the upper front edge being 55 inclined as best shown at 69, at the angle desired for the inclined top of the curb. The length and width of the division plate are the same as the height and thickness, respectively, of the concrete curb which is to be constructed. A tab or ear 70 can be formed at the top of each of the division plates 68 and is shown as provided with a hole 71. Each of the division plates 68 can also be provided on the upper rear edge thereof with a block 72 of substantial size which projects rearwardly from the plate and is adapted to rest on the upper flange 24 of the rear rail 20 to hold the division 60 plate in proper position. The blocks 72 are preferably rigidly attached, as by welding, to the upper edges of the division plates 68.

The rails 20, 21 are held against the rear and front sides of the division plates 68 by ties constructed as best 70 shown in Fig. 4 and which are the subject of this invention, these ties also holding each companion pair of

stakes 54 against spreading or other displacement. Each of these ties, indicated generally at 75, is in the form of a rigid metal strap 77 having one end reversely bent to provide an end hook 76, this hook being of a size to embrace the corresponding stake 54, the latter being shown as being round in cross section. The opposite end of each strap 77 is bent laterally to provide a flange 78 which extends from the same side of the strap 77 as the hook 76. Each strap also has welded thereto an L-shaped bracket 79, this bracket having a leg 80 which is arranged in parallel spaced relation to the flange 78. The spacing of the leg 80 from the flange 78 is approximately equal to the thickness of each stake 54 and the flange 78 and leg 80 are provided with alining holes 81 and 82, respectively. These holes are arranged to receive a tapered pin or nail 83. The tapered shank 84 of this pin enters the holes 81, 82 and forms a wedge or cam for wedging or camming the corresponding stake 54 against the back of the tie 75. To facilitate removal, the pin or nail is provided with a head 86.

The upper front channel members or rails 22, the flat webs 60 which form the inclined upper surface of the curb front, are held in position against the inclined front edge portions 69 of the division plates 68 by metal U-clamps 85. Each clamp is made in the form of a rigid metal strap and comprises a horizontal cross part 87, a depending vertical rear leg 88 and a downwardly and forwardly inclined front leg 89. The lower extremity of the front leg 89 terminates in a reversely bent or hooked portion 90 which inclines downwardly and rearwardly, that is, downwardly and toward the rear leg 88. This rear leg 88 is disposed substantially perpendicularly to the cross part 87 while the other leg 89 extends from the cross part 87 at an obtuse angle which is preferably generally the same as the angle to the horizontal formed by the inclined edge portion 69 of each of the plates 80.

In erecting or setting up curb forms as above described, the following procedure has been found convenient although other sequences of steps may be used.

A rear channel member or rail 20 and a lower, front channel member or rail 21 are placed on edge on the graded ground in upright spaced relation and division plates 68 are placed between them at suitable intervals with the blocks 72 thereof resting on the top of the rail 20. Pairs of stakes 54 are then driven into the ground along the outer sides of the front and rear rails 20 and 21. Each front stake is driven downwardly in contact with the flanges 46 and 47 of the lower front rail 21 and also in contact with the inner face of the leg or flat finger 56 of the stake bracket 52 welded to one end of the lower front rail 21. Each rear stake 54 is driven to aline with its companion front stake 54 and is driven downwardly in contact with the flanges 26 and 27 of the corresponding back rail 20.

Each pair of stakes is then connected and alined with a tie 75. This connection is quickly effected by hooking the hooked end 76 of the tie over one of these stakes and then swinging the tie horizontally to place the companion stake 54 between the flange 78 and the leg 80 of the bracket 79. Each tie is then latched by driving the wedge shank of the pin or nail shown in Fig. 5 through the holes 81, 82 so as to confine the corresponding stake 54 in the hook provided by the flange 78 and leg 80. Any irregularity in driving the stakes is overcome by the requirement that the front stake 54 be in contact with the flanges 46 and 47 of the lower front rails, this being assured by the stake bracket 52, and by the requirement that the upper end of the rear stake 54 be in contact with the flanges 26 and 27 and also in proper position with reference to the companion front stake 54, this being assured by the tie 75.

The upper front rails 22 are then placed on top of the lower front rails 21 and are laid back so as to engage with the inclined edges 69 of the division plates 68.

A wooden block 92 is then placed against the rear face of the web 23 of the rear rail 20 in line with the division plate 68 and the rear leg 88 of a U-clamp 85 is placed against the inner face of the block. The front leg 89 of this U-clamp is then stressed forwardly and the U-clamp pushed down. When the hooked end 90 of the front leg passes below the flange 46 of the lower front rail 21, the U-clamp is released so that this hook 90 hooks under this flange 46, as best shown in Fig. 1, thereby to prevent the U-clamp from working its way upwardly due to its wedge shaped form and its inherent resiliency.

Concrete can then be poured in the mold provided by the assembled forms. When the concrete has taken its initial set, the U-clamps 85 can be removed to permit taking off the upper front rails 22 so that the upper front and top of the concrete curb can be brushed and smoothed or finished while the concrete is still fresh. After the concrete has set, the wedge pins or nails 54 can be withdrawn from the holes 81, 82 whereupon the tie bars 76 can be swung horizontally with the hooks 76 as a pivot, thereby to free the corresponding stake 54 from the flange 76 and leg 80 of each tie bar. Each tie bar 75 can then be moved longitudinally to free its hooks 76 from the opposite stake.

With the rear rail 20 still in position, a tool can be inserted in the hole 71 of each division plate 68 and the flange 24 of the rail 20 used as a fulcrum to draw the division plate upwardly. Following this, the stakes 54 can be pulled and the rails 20, 21 and 22 stripped from the form. It will be noted that the division plates 68 serve not only to space the rails 20, 21 and 22 of the forms, but also provide expansion joints at intervals along the length of the curb.

From the foregoing, it will be seen that the tie 75 can readily be hooked by the hooks 76 around the stake and then swung horizontally so as to receive a companion rear stake 54 and to hold this rear stake in firm engagement with the flanges 26 and 27 of the rear rail 20. It will also be seen that the wedge pin shown in Fig. 5 insures that these ties 75 remain attached to the stakes 54 until the ties are deliberately released by withdrawing these pins.

I claim:

1. In a curb form having side mold sections spaced to form the sides of the curb from Portland cement poured therebetween, pairs of stakes driven into the ground on opposite sides of the curb form along the outer sides of said mold sections and projecting above said mold sections, and means connecting said mold sections to said stakes, the combination therewith of means for spacing the stakes of each pair at a predetermined distance from each other and holding the stakes of each pair at such predetermined distance while said poured Portland cement is setting, comprising a metal strap having a generally straight body part, a horizontally and reversely extending integral hook forming one end of said body toward the opposite end of said body and said hook fitting around the upper end of one of said stakes and to rotate around said one of said stakes as a pivot in a horizontal plane, a pair of spaced flanges permanently fixed to and projecting laterally and horizontally in the same direction from said opposite end of said body and spaced from each other a distance approximately equal to the thickness of said stakes, said flanges being provided, at a distance from said body approximately equal to the thickness of said stakes, with holes in horizontal alinement with each other along a line generally parallel with said body, and a pin extending through said holes and arranged to retain a stake from displacement from between said flanges, said flanges being spaced from said hook a distance approximately equal to said predetermined distance whereby upon hooking said hook around one stake said body can be swung

in a horizontal plane to bring its flanges toward the companion stake can be brought between said flanges to position the stakes at said predetermined distance, said pin being thereafter insertable through said holes to retain said flanges from displacement from said companion stake.

2. A tie as set forth in claim 1 wherein said pin is of diminishing size in cross section toward one end to wedge the upper end of said companion stake against said body.
